UNITED STATES PATENT OFFICE.

OTTO H. HARTMANN, OF CASSEL-WILHELMSHOHE, GERMANY, ASSIGNOR TO
SCHMIDT'SCHE HEISSDAMPF-GESELLSCHAFT M. B. H., OF CASSEL-WIL-
HELMSHOHE, GERMANY, A CORPORATION OF GERMANY.

MEANS FOR REGULATING STEAM POWER AND HEATING PLANTS.

Application filed July 3, 1922, Serial No. 572,702, and in Germany July 11, 1921.

My invention relates to plants in which a steam boiler heated by a furnace is combined with a steam engine and with a device in which the exhaust of such engine is utilized for heating purposes. In plants of this character there are very frequently wide fluctuations in the consumption of steam. Attempts to compensate for these fluctuations, made hitherto, have been based on the use either of boilers having an extra large water space, or of exhaust steam accumulators. Boilers of the type just referred to permit only a relatively low pressure of live steam to be produced, so that the pressure of the heating steam (exhaust steam) will be correspondingly low. Exhaust steam accumulators, if they are to be efficient, are very expensive to construct. To be efficient, such accumulators must be of very large volume, and even then only a low pressure can be used for the heating steam. The best results are obtained if the initial pressure (that is, the pressure at which steam is admitted to the engine) is as high as possible, for instance 30 atmospheres or more. In this case the work that may be obtained from the steam (in the engine) is considerable even if the counter-pressure (at the heating device) is high, but the high pressure boilers necessary in this case have but a very limited water capacity. Such boilers, therefore, are very sensitive to wide fluctuations in the demand for heating steam and will, in that case, supply live steam of greatly varying pressure, which results in an uneconomical utilization of the steam as regards production of power.

The object of my present invention is to reduce, as far as possible, the fluctuations of the steam pressure in the boiler of a steam power and heating plant of the character mentioned above, particularly when operating with a live steam pressure of 30 atmospheres or more. Another object is to reduce the size of the exhaust steam accumulators in cases where their use is unavoidable and thus to bring down the cost of the plant to a reasonable figure. To accomplish this result, I have devised the plan of controlling the boiler furnace by the pressure of the heating steam in such a manner that when the amount of steam required for heating purposes increases, combustion in the furnace will be made more lively, but checked

when the amount of steam required for heating purposes decreases. This may be accomplished, for instance, in a plant which includes an automatically-stoked step-grate furnace, by having a pressure-operated regulator, connected with the heating steam conduit, shift the stack-damper in accordance with the requirements of air for supporting combustion, or, in a plant having a chain-grate furnace, such pressure-operated regulator would be arranged to increase or decrease the feed velocity of the chain-grate and, by controlling the boiler draft, to increase or decrease the amount of air for supporting combustion. By means of my improved apparatus an automatic regulation of the furnace is obtained and the efficiency of the plant will no longer depend in the same degree upon the watchful care of the attendants. Only under exceptional circumstances will the engineer in charge of the boiler have to supplement by hand the automatic regulation obtained by my invention.

The drawing shows two forms of the invention. Fig. 1 is a diagrammatic arrangement of the invention as applied to an automatically stoked step-grate furnace, parts being shown in vertical section to illustrate the internal construction; and Fig. 2 is a similar view illustrating the application of the invention to an automatically stoked chain-grate furnace.

A (Fig. 1) designates a counter-pressure steam engine of the reciprocating-piston type, receiving live steam from the boiler B by way of a pipe a. The boiler is heated by means of a furnace having a step-grate b. The exhaust steam of the engine A passes through a pipe c to a cross C and from there a part of the exhaust steam passes through a branch pipe c¹ to a heating apparatus C¹. The water of condensation leaves at C². Further, a part of the exhaust steam passes from the cross C through a branch pipe c² to an evaporating apparatus C³. The water of condensation leaves at C⁴. The liquid to be evaporated enters the apparatus at C⁵, passes through the heating pipes C⁶ and leaves the apparatus as steam at C⁷. In the pipes c¹ and c² stop valves c⁸ and c⁹ respectively are arranged. The cross C is further connected by a pipe d with a pressure-operated regulator D. This regulator may comprise a cylinder E containing

a sliding piston F exposed on one face to the pressure of the heating steam which enters said cylinder through the pipe d, and on the other face to the pressure of a spring e, it being understood that the cylinder is open to the air on the spring side, so that the piston may move freely in response to variations in the steam pressure acting on its lower face. The piston rod f is connected 10 pivotally with a lever G, said lever being connected operatively with the damper H arranged in the smoke flue or stack connection J of the boiler furnace. The connection of the damper with the lever G is made 15 by means of a chain or wire K engaging guide rollers L, L¹ and connected with the said lever. In the present example the transmission of the movements of the piston F of the pressure-operated regulator D to 20 the stack-damper H is not effected directly, but by means of a servo-motor, to permit the apparatus to be more compactly built and occupy less space, of the pressure-operated regulator. For this purpose, between 25 the chain K and the lever G, the rod M of the piston O of the servo-motor is inserted, the cylinder N of which is filled with a pressure liquid. This liquid is admitted by the channels Q and P to the cylinder compartments located on both opposite sides of the piston O, or is discharged from such compartments through said channels. The channels P and Q are controlled by a piston valve S, the rod T of which is pivotally connected at g with the lever G, and the casing R of which is provided with a central flanged inlet R¹ and with upper and lower flanged outlets R², R³ for the pressure liquid. 30 The guide rollers L turn about stationary axes, but the roller L¹ turns about an axis that may be adjusted up or down by means of a wire or chain U winding on a drum V rotatable about a stationary axis. By turning the crank handle W, the operator will 35 cause the roller L¹ to be raised or lowered and the damper H to be lowered or raised respectively. This is the manually-actuated regulator.

The automatic regulation of the damper H, and therefore of the rate of combustion in the boiler furnace, operates as follows: The drawing shows in full lines the lever G and also the other parts of the regulator in middle position. Also the stack damper H is shown in middle position and the pressure is equal on both sides of the piston O of the servo-motor. Now, if for instance the pressure of the exhaust steam in the pipe c rises, because the engine discharges more exhaust steam than is used for the heating apparatus C¹ and C², then by this increased pressure the piston F of the pressure regulator D is lifted against the compression of the spring e. Owing to the fact that, as mentioned above, the pressure is the same on

both sides of the piston O the connecting point G¹ between the lever G and the piston rod M of the servo-motor must be considered as fixed at first. Consequently, if the piston F is rising, the piston valve rod T is also taken along and the piston valve S opens the channels P and Q. The pressure liquid above the piston O can be discharged by the channel P and the outlet R², whereas pressure liquid enters through the channel Q underneath the piston O. The latter is thereby lifted, the stack-damper H is lowered by means of the chain K and the combustion in the furnace is checked. When the piston O is moving upwards, the point G¹, of course, passes into the upper position G² marked by a broken line. If the pressure of the heating steam should decrease, the spring e will press the piston F down contrary to the steam pressure working upon its underside and takes along the piston valve S. Thereby a connection between the channel Q and the flanged outlet R² is established, whereas the channel P is put into connection with the flanged inlet R¹. The pressure liquid therefore can pass to the underside of the piston O and press the latter down. The point G¹ passes into the lower position G³. The damper H is lifted by the chain K and thereby the combustion in the furnace is made more lively.

In the form of my invention shown in Fig. 2 the effect of the servo-motor with respect to shifting the stack-damper H is the same as in Fig. 1. In Fig. 2 the steam generating plant is provided with a chain-grate b¹, the feed velocity of which is controlled by the servo-motor in accordance with the fluctuations of the heating steam pressure. The chain grate b¹ is driven by an electric motor U¹ by means of a belt drive (flexible gearing) U² and of a worm gear U³. A two-armed switch lever V³ pivotally mounted at V⁴ is adapted to slide with its one end over contacts V¹ of the regulating resistance V² for the motor U¹ and is with its other end joined with the piston rod M of the servo-motor. Thus the lever V³ is controlled by the movements of the piston O.

The arrangement described above works in the following way:

The middle position of the lever V³ is indicated on the drawing by full lines. Now, if the pressure of the heating steam rises, the piston O of the servo-motor will rise in the manner described with reference to Fig. 1 and will lower the stack-damper H by means of the chain K. At the same time the upright arm of lever V³ passes from its middle position into the right end position and thereby inserts more resistance into the circuit for the motor U¹, so that the latter and consequently also the chain-grate b¹ will run slower.

For this reason, the steam production is

reduced. When the heating steam pressure is sinking, the piston of the servo-motor moves downwardly, the stack-damper H is opened more widely and the lever V³ is brought into the left end position. The motor U¹ and the chain-grate b¹ will run faster, so that an increased steam production takes place.

Various modifications may be made without departing from the nature of my invention as set forth in the appended claims.

I claim:

1. In a power plant, power developing means, a boiler for supplying steam to said power developing means, a furnace for said boiler, means for controlling the rate of combustion in said furnace, a single exhaust conduit leading from said power developing means, a device for utilizing the exhaust steam, a regulator branched off the exhaust conduit, said regulator being responsive to variations in the condition of said exhaust steam, and means for connecting said regulator to the combustion controlling means, whereby the rate of combustion in said furnace is increased or decreased in accordance with the requirements of said steam utilizing device.

2. In a power and heating plant, a steam engine, a boiler for supplying steam to said engine, a furnace for said boiler, means for controlling the rate of combustion in said furnace, a single exhaust conduit leading from said engine, a device for utilizing the heat of the exhaust steam, a regulator branched off the exhaust conduit, said regulator being responsive to variations in the condition of said exhaust steam, and means for connecting said regulator to the combustion controlling means whereby the rate

of combustion in said furnace is increased or decreased in accordance with the amount of exhaust steam required by said heat utilizing device.

3. In a power plant, a single power developing means, a boiler for supplying the steam to said power developing means, a furnace for said boiler, means for controlling the rate of combustion in said furnace, an exhaust conduit leading from said power developing means, a device for utilizing the exhaust steam, a regulator branched off the exhaust conduit, said regulator being responsive to variations in the condition of said exhaust steam, and means for connecting said regulator to the combustion controlling means, whereby the rate of combustion in said furnace is increased or decreased in accordance with the requirements of said steam utilizing device.

4. In a power and heating plant, a single steam engine, a boiler for supplying steam to said engine, a furnace for said boiler, means for controlling the rate of combustion in said furnace, an exhaust conduit leading from said engine, a device for utilizing the heat of the exhaust steam, a regulator branched off the exhaust conduit, said regulator being responsive to variations in the condition of said exhaust steam, and means for connecting said regulator to the combustion controlling means, whereby the rate of combustion in said furnace is increased or decreased in accordance with the amount of exhaust steam required by said heat utilizing device.

In testimony whereof I have hereunto set my hand.

OTTO H. HARTMANN.
